Primary Examiner—Dominic Simone(74) *Attorney, Agent, or Firm*—Schmeiser, Olsen & Watts(57) **CLAIM**

The ornamental design for the fingernail enhancement, as shown.

DESCRIPTION

This application is related to a copending utility patent application by Michele Washington entitled “Apparatus and Method for Covering Fingernails”, U.S. Ser. No. 09/324, 680, filed Jun. 3, 1999.

FIG. 1 is a perspective view of a fingernail enhancement showing my new design;

FIG. 2 is a top plan view of the fingernail enhancement in FIG. 1;

FIG. 3 is a side elevational view of the fingernail enhancement in FIG. 1;

FIG. 4 is a front elevational view of the fingernail enhancement in FIG. 1;

FIG. 5 is a bottom plan view of the fingernail enhancement in FIG. 1; and,

FIG. 6 shows a cross-sectional view of the fingernail enhancement in FIG. 1 taken along line 6—6 shown in FIG. 6.
